UNITED STATES PATENT OFFICE.

THOMAS WALLACE, OF VALPARAISO, INDIANA.

APPARATUS FOR CLEANING CHALK-BOARD ERASERS.

1,062,311.

Specification of Letters Patent.

Patented May 20, 1913.

Application filed August 1, 1910. Serial No. 575,038.

To all whom it may concern:

Be it known that I, THOMAS WALLACE, a subject of the King of Great Britain, and residing at Valparaiso, in the county of 5 Porter and State of Indiana, have invented new and useful Improvements in Apparatus for Cleaning Chalk-Board Erasers.

Generally stated, my device is constructed to closely resemble the form of a ladder having a relatively large number of rungs or treads spaced at comparatively short distances apart. The device is placed in a horizontal position over the chalk-trough at the base of the black-board in connection with 10 which it is to be used; or in the absence of a trough usually provided on a black-board, the device may be provided with a bottom which is attached thereto for receiving the fine particles of chalk which are removed 15 from the eraser in the cleaning operation, the combined cleaner and chalk-receiving device being attached to the base of the black-board.

My object is to provide a cleaner-device 20 which will operate to clean the erasers quickly and efficiently, and which may be located closely adjacent to the black-board, thereby permitting the erasers to be effectively cleaned without removing them from 25 the room in which the board is located, as is the usual practice.

Referring to the accompanying drawing— Figure 1 is a perspective view of a portion of a black-board equipped with a chalk-cleaning device constructed in accordance 30 with my invention, the cleaner-device in this instance being shown as extending over the chalk-trough forming a part of the black-board structure. Fig. 2 is a broken enlarged 35 plan view of one end of the cleaner-device 40 illustrated in Fig. 1. Fig. 3 is a section taken at the line A—B on Fig. 2 and viewed in the direction of the arrow. Fig. 4 is an end view of a part of the cleaner-device 45 showing one of the ways in which it may be secured to the chalk-trough. Fig. 5 is an end view of a modification of the cleaner-device illustrated in Fig. 2. Fig. 6 is a 50 broken plan view showing another form in which my invention may be provided. Fig. 55 7 is a section taken at the line C—D on Fig. 6 and viewed in the direction of the arrow. Fig. 8 is a section taken at the line M—N on Fig. 6 and viewed in the direction of the 55 arrow; and Fig. 9, an end view of a modification of the device illustrated in Fig. 6.

Referring particularly to Figs. 1 to 4 inclusive, a black-board in connection with which my improved cleaner-device is illustrated, is represented at 11, the black-board in this instance, as is usual in practice, being provided with a chalk-trough 12, in connection with which the cleaner-device of the figures referred to is used. The cleaner-device comprises a pair of parallel bars 13, 13 which are spaced apart as represented and are connected together by a series of, preferably, parallel bars 14. The bars 14 are formed of wire and at their opposite ends are looped about the bars 13 as represented 60 at 15, at which loop-portions the bars 14 are firmly secured in spaced relation, preferably from one-sixteenth to seven-sixteenths inches apart, the bars 14 preferably extending below the plane occupied by the bars 13 as 65 70 75 illustrated in Fig. 3, whereby the last referred to bars operate to form a ledge to prevent the sticks of chalk, laid upon the cleaner-device, from rolling to the floor. The cleaner-device formed of the bars 13 80 and 14 may be held upon the trough 12, to extend across the top thereof, in any suitable manner, as by hinges (not shown) or through the medium of clips 16 which would be secured as at the screws 17 to the back 85 edge of the trough, the rear one of the bars 13 resting in the clips, so provided near its opposite ends.

Referring to Fig. 5, the construction therein shown comprises a pair of spaced parallel 90 bars 18 which may be formed of wood and correspond with the bars 13. In this case, the transverse cleaner bars represented at 19 and spaced apart as explained of the construction shown in Fig. 2, are set into openings 20 in the inner faces of the bars 18. In this construction, provision is made for catching and retaining the chalk which falls from the eraser during the cleaning operation, this being accomplished by means of a 95 horizontal plate 21, which may be of metal secured to the under sides of the bars 18 and extending the full length of the device.

Referring to Figs. 6, 7 and 8, I have shown an embodiment of my invention constructed from a single sheet of metal and formed by slitting and stamping the metal. In this construction, the metal is slit along, preferably, parallel lines transversely of the sheet thereof, but short of its lateral edges, 100 to provide a series of parallel transverse webs or bars 22 which, in the operation of 105 110

- forming the metal to shape, are bent at preferably right-angles to the body-portion of the sheet, as illustrated in Fig. 8, to cause the greater surfaces of the bars 22 to extend at 5 an angle, preferably a right-angle, to the plane of the cleaner-device. The lateral edge-portions 23 and 24 of the sheet form connecting bars for the transverse webs or bars 22 and correspond to the bars 13 of Fig. 10 2. It is preferred that the metal forming the bar 24 be bent upwardly at an angle to the body of the cleaner-device as represented at 25 and formed into a bead 26 to extend longitudinally of the cleaning-device along 15 its front side for preventing sticks of chalk placed on the cleaner-device from dropping to the floor.

- The device illustrated in Figs. 6, 7 and 8 is designed for use in connection with a black-board in which a trough, such as that represented at 12 in Fig. 1, is provided, the cleaner-device in use extending over the top of the trough. When the device is to be used in connection with a black-board having 20 no trough, I prefer to form a device similar to that shown in Figs. 6, 7 and 8 with a base-plate represented at 27, which would preferably be formed integral with the bars 23 and 24, as illustrated in Fig. 9. 25 30 The operation of the device is as follows: The erasers are cleaned by laying them upon the transverse cleaner-bars described and drawing them across these bars, with the result of removing the fine chalk particles 35 from the eraser, whereupon they fall to the chalk-receiver below.

It will be manifest from the foregoing that by constructing a chalk-cleaning device in accordance with my invention, erasers 40 may be readily and effectually cleaned, and the chalk particles removed therefrom intercepted by the chalk-receiver.

What I claim as new, and desire to secure by Letters Patent, is—

- 45 1. The combination with a blackboard, of an eraser-cleaning device in the form of a grid supported adjacent to said board and comprising side-members extending lengthwise of said board and cross-bars extending 50 transversely thereof to afford transversely extending cleaning ribs.

2. The combination with a blackboard, of a trough supported adjacent to said board and a grid supported to extend over said 55 trough for cleaning said erasers when the

latter are rubbed across said grid and comprising side-members extending lengthwise of said trough and cross-bars extending transversely thereof to afford transversely extending cleaning ribs.

3. The combination with a blackboard, of a trough supported adjacent to said board, a grid supported to extend over said trough, and comprising side-members extending lengthwise of said trough and cross-bars extending transversely thereof to afford transversely extending cleaning ribs and a ledge 60 extending along the front edge of said grid, for the purpose set forth.

4. The combination with a blackboard and its trough at the lower end thereof, of a grid supported to extend over said trough for cleaning erasers when the latter are rubbed across the grid, and comprising side-members extending lengthwise of said trough 70 and cross-bars extending transversely thereof to afford transversely extending cleaning ribs, for the purpose set forth.

5. The combination with a blackboard and its trough at the lower end thereof, of a grid supported to extend over said trough for cleaning erasers when the latter are rubbed across the grid, and comprising side-members extending lengthwise of said trough 80 and cross-bars extending transversely thereof to afford transversely extending cleaning ribs, and a ledge extending along the front edge of the grid, for the purpose set forth.

6. The combination with a blackboard, of an eraser-cleaning device secured to said 90 blackboard and comprising a trough and a grid-covering therefor formed of side-members extending lengthwise of said trough and cross-bars extending transversely thereof to afford transversely extending cleaning 95 ribs, for the purpose set forth.

7. The combination with a black-board, of a combined integral eraser-cleaning device and trough therefor mounted on the board and comprising a base-plate forming the 100 base of the trough, uprights connected with said base-plate, a series of transversely-extending bars connected with one of said uprights, and an upwardly-extending plate, forming a ledge, connected with the other of 105 said uprights.

THOMAS WALLACE.
